Attorneys.

UNITED STATES PATENT OFFICE.

D'ARCY J. M. LECK, OF MINNEAPOLIS, MINNESOTA.

BUILDING CLAMP.

Application filed July 17, 1926. Serial No. 123,129.

My invention relates to building clamps, and an object is to provide a device of this character for securing together two pieces of timber in such manner that the clamp may be readily removed whenever desired and reused. An object in particular is to provide a clamp for securing a piece of wood to a post in such manner that the clamp may be removed while leaving the post standing. My device is adapted especially for use in connection with staging or false work employed in the laying of cement floors.

The full objects and advantages of my invention will appear in connection with the detailed description thereof, and the novel features of my inventive idea will be particularly pointed out in the claim.

In the accompanying drawings which illustrate a practical embodiment of my invention,

Fig. 1 is a view showing the clamp in elevation and used in connection with the false work for a cement floor. Fig. 2 is a view at right angles to Fig. 1. Fig. 3 is a plan view of the clamp.

As shown in the drawings, the clamp consists of a substantially U-shaped member having two side arms 10 and 12 and a connecting end member 14. The free end of the arm 10 is bent to form a hook 16 as best shown in Fig. 2 while the free end of the arm 12 is bent over to form an eye 18 upon which is pivoted a bar 20 which forms a fourth side for the clamp. It will be apparent from Fig. 3 that one end of the bar 20 is provided with a hole through which a portion of the eye 18 is passed before being entirely bent over. In order that the inner edge of the bar may extend straight across when the clamp is in use, the outer edge of the bar is cut away toward its free end as indicated at 22 for engaging the hook. This cut away edge as will be apparent is adapted to swing into contact with the curved portion of the hook.

The operation and advantages of my invention will now be obvious. Referring to Figs. 1 and 2, a temporary floor F is partly supported by posts P to which blocks B are secured by the clamps any number of which may be employed according to the number of posts. These blocks support horizontals or beams H which in turn support stringers S on which the temporary floor F rests. It will be noted from Fig. 2 that the clamps when positioned for use occupy an inclined position and that the weight carried by the blocks cause a binding or clamping action. In case the clamp does not bite into the wood sufficiently for holding the parts firmly together, nails N may be driven into the wood below the end member 14 and above the pivoted bar 20, thereby effectively preventing liability of the clamp slipping. After the cement C has been poured, the blocks B, the beams H and stringers S are soon thereafter removed upon releasing the clamps. The posts P are ordinarily left standing for about three weeks. The clamps can be readily removed from the posts for immediate re-use on account of the detachable engagement of the pivoted bar 20 with the hook 16. The provision of the eye 18 prevents the bar from becoming entirely detached and lost.

I claim:

A building clamp comprising a U-shaped member having a hook at one end thereof and an eye at the other end thereof and a flat bar pivotally connected at one end with said eye and detachably engaging said hook at the other end, the outside edge of said bar being cut to reduced width at the last mentioned end in order that the inside margin of the bar may extend perpendicularly to the arms of the U-shaped member when the clamp is in use.

In testimony whereof I hereunto affix my signature.

D'ARCY J. M. LECK.
